(57) **CLAIM**

The ornamental design for a razor package, as shown and described.

DESCRIPTION

FIG. 1 is a perspective view of a razor package showing our design as seen from the top, front and left side;

FIG. 2 is a front elevational view thereof;

FIG. 3 is a left side elevational view thereof, the right side elevational view being a mirror image;

FIG. 4 is a rear elevational view thereof;

FIG. 5 is a top plan view thereof; and,

FIG. 6 is a bottom plan view thereof.

The dot-dash line in FIGS. 1, 2, 4 and 5 showing a razor enclosed in the package is for illustrative purposes only and forms no part of the claimed design.

1 Claim, 4 Drawing Sheets
